(57) **CLAIM**

The ornamental design for mini-clip, as shown and described.

DESCRIPTION

FIG. 1 is a front perspective view of a mini-clip showing my new design;

FIG. 2 is a rear perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof; and,

FIG. 8 is a rear view thereof.

The broken line showing of a circle on FIG. 4 is for illustrative purposes only and forms no part of the claimed design.
